Levinsky Block
ATTORNEY

UNITED STATES PATENT OFFICE.

JOEL SASIENI, OF LONDON, ENGLAND, ASSIGNOR TO MAURICE RAPOORT AND EUGENE J. RICH, COMPOSING THE FIRM OF MAURICE RAPOORT & COMPANY, OF NEW YORK, N. Y.

POCKET LIGHTER.

Application filed February 19, 1926, Serial No. 89,254, and in England October 3, 1925.

This invention relates to improvements in portable igniters adapted for use in lighting cigars, etc., and the main object of the invention is to provide such an igniter with a self fuel filler.

Another object of the invention is to provide such an igniter with an absorbent agent that will allow a free flow of fuel to the wick.

10 A further object of the invention is to provide means for operating the flint engaging wheel without any fear of burning the fingers or breaking the thumb-nail.

15 Other important objects and novel features of my invention will become apparent as the specification proceeds.

In the drawings forming a part of this specification,

20 Figure 1 is a front view in elevation of my improved lighter with the wick covering cap in open position.

Figure 2 is a longitudinal section on line "2—2" of Fig. 1 and

25 Figure 3 is a detail view in section of the self filler chamber.

Referring to the drawings in detail 5 indicates the igniter as a whole, comprising a body portion 6 provided at the upper end thereof with a wick guide 7 through which

30 a wick 8 may be inserted and maintained in proper position for use when required. A cap 9 pivoted at 10 may be employed to protect the wick when not in use. The cap 9 is pivoted on the upper portion of a tubular

35 magazine 11 fixed to the body 6 in which may be stored pellets 12 of flint that are supported on a spring 14 whose tension is adjusted by a screw 15 that screws into the bottom of the magazine and exerts a pres-

40 sure on an ear 16 of the cap 9 and tends to maintain the cover or cap 9 in open or closed position as the case may be. There is also fixed to the body 6 a tubular container 17 in

45 which is contained a flint pellet 18 that is pressed upwardly against the corrugated surface of a steel wheel 19 which may be operated for producing a spark to ignite the wick 8 by turning thumb nut 21 on a shaft 20 upon which the wheel 19 is fixedly mounted. The pellet 18 is maintained in

50 constant engagement with the wheel 19 by a spring 22 that is tensioned by a screw 23 at the lower end of the container 17.

Fuel of any suitable nature for the purpose such as benzine, denatured alcohol or 55 the like is fed to the wick 8 by means of rods or wires 24 covered with any suitable absorbent material such as cotton, wool, etc., extending substantially the entire length of the body 6. The body 6 has at its lower end 60 a reduced portion 25 over which there fits snugly a tubular chamber 26 provided at its lower end a ball valve 27 terminating in a threaded extension or nipple 28 having an opening 29 therein normally closed by a 65 cap 30.

When it is desired to fill the igniter with fuel, the cap 30 is removed by unscrewing same from the nipple 29, and the nipple is inserted into the fuel and the body portion 70 6 is drawn upwardly with one hand while the chamber 26 is held with the other hand. The fuel will be sucked up through the opening 29 and will open the valve 27 by raising a ball 31 off its seat and will enter the chamber 26 to be absorbed by the absorbing agents 24 and led up to the wick 8 which will become saturated with the fuel and be ready for ignition when required. It will be noted that the ball valve will prevent any of the 75 fuel from oozing or leaking out from the igniter.

80 From the foregoing it will be seen that I have produced an improved cigar lighter provided with a self filler, a wick protecting cap that will be positively held in open or closed position and means for igniting the lighter without danger of burning the fingers or breaking the thumb-nail.

Having described my invention, what I 85 claim and desire to secure by Letters Patent is:

1. An igniter of the class described comprising a body, a wick extending from the body, spark producing means, fuel absorbing and storing means and self-filling means.

2. An igniter of the class described comprising a body, a wick extending from the body, spark producing means, fuel absorbing and storing means, self-filling means, and a 100 thumb nut associated with the spark producing means adapted to operate said spark producing means.

3. An igniter of the class described comprising a body, a wick extending from the 105 body, spark producing means, fuel absorb-

- 2
- ing and storing means, self-filling means, and a normally closed valve associated with the self-filling means adapted when opened to admit fuel into the igniter.
4. An igniter of the class described comprising a body, a wick extending from the body, spark producing means, fuel absorbing and storing means, self-filling means comprising, a chamber frictionally associated with the body portion and a ball valve mounted within the chamber.
5. An igniter of the class described comprising a body, a wick extending from the body, spark producing means, fuel absorbing and storing means, self-filling means comprising, a chamber frictionally associated with the body portion, a ball valve mounted within the chamber, a projection having an inlet opening therein associated with the chamber and a cap on said projection adapted to normally close said opening.
6. An igniter of the class described comprising a body, a wick extending from the body, spark producing means, fuel absorbing and storing means, self-filling means, a magazine chamber associated with the body portion adapted to contain spark producing pellets, a cap pivoted in said magazine chamber adapted to normally cover the wick, a spring within the magazine chamber adapted to exert a tension on said cap and a screw
- within the chamber adapted to adjust the tension of said spring.
7. An igniter of the class described comprising a body, a wick extending from the body, spark producing means, tensioning means associated with said spark producing means, a thumbnut associated with the spark producing means adapted to operate same, a magazine chamber fixed to said body portion, a cap pivoted on said chamber, cap tensioning means within said chamber, covered wires within the body adapted to be used as fuel absorbing and conducting agents, a reduced portion on said body, a chamber frictionally associated with said body, a ball valve in the chamber, an extension on said body having an opening therein leading into the chamber and a cap adapted to be unscrewed when fuel is to be fed to the igniter.
8. In combination with an igniter, a chamber and suction means for filling the chamber.
9. In combination with an igniter, a suction chamber adapted to be operated to fill the igniter with fuel and a suction operated ball valve within said chamber.
- 55
In testimony whereof I hereunto affix my signature.

JOEL SASIENI.
